PRESSURE FRYER

Robert G. Wilson, 643 E. Faris Road, and Raymond W.
Rogers, 414 Potomac Ave., both of Greenville, S.C.
29605

Filed Oct. 2, 1968, Ser. No. 13,820

Term of patent 14 years

Int. Cl. D12—04

U.S. Cl. D81—10

Fig. 1.

Fig. 2.

*Fig. 3.**Fig. 4.*

FIG. 1 is a left front perspective view of a pressure fryer, showing the new design;

FIG. 2 is a right front perspective view, with the lid open and the basket in raised position wherein the basket is included in broken lines for illustrative purposes only;

FIG. 3 is a top plan view;

FIG. 4 is a rear elevational view.

We claim:

The ornamental design for a pressure fryer, as shown and described.
